UNITED STATES PATENT OFFICE.

GIUSEPPE GUADAGNI, OF TURIN, ITALY.

APPARATUS FOR THE FORMATION OF NITRIC ACID OR HYDROCHLORIC ACID.

Application filed January 13, 1925, Serial No. 2,201, and in Germany December 12, 1924.

The manufacture of hydrochloric acid and nitric acid has been effected till now by causing a predetermined quantity of either common salt (for hydrochloric acid HCl) or sodium nitrate (for nitric acid HNO₃) to react when heated with a corresponding quantity of sulphuric acid in suitable cast iron containers. Said containers are located in refractory furnaces provided at their upper part with outlets for the evolved acid gases, which are then conveyed into condensing and absorbing apparatus.

The molten sodium bisulphate (when HNO₃ is manufactured) issues through the lower openings of the cast iron containers, while—when HCl is manufactured—the bisulphate is caused to act with a fresh quantity of salt at a higher temperature in another part of the furnace (in the muffle) nearer to the firing, until it is converted into neutral sulphate of soda, while at the same time a new formation of hydrochloric acid gas takes place.

The charging of salt and discharging of the products of the above named reactions are effected at intervals of generally six hours; these operations require time and handwork and mean a loss of heat and acid gases and harm to the operators' health, as the work must be carried on in rooms saturated with hot and irritating acid vapours and poisonous gases.

All these inconveniences are removed by the automatically and continuously working apparatus forming the object of this invention permitting of the commercial formation of nitric acid or hydrochloric acid and sodium bisulphate.

This apparatus is substantially constituted by an elliptical container, (in which the sulphuric acid is caused to act on common salt or sodium nitrate) and a hopper through which the salt is fed into the container by means of a short and wide conveyor screw. A suitable device, (to which the movement of said conveyor screw is transmitted) serves to admit into the container the quantity of sulphuric acid that is necessary for dissociating the salt issuing from the conveyor screw in the unit of time. A pipe reaching near the bottom of the container and issuing through the wall thereof at a certain height serves for the continuous discharge to the outside of the sodium bisulphate that is gradually formed. The elliptical container is tightly closed by means

of a cover consisting of refractory, preferably siliceous, material that will not be deteriorated by the acid at a high temperature. Said cover is provided on each side with an opening, the front opening serving for the admission of salt and acid and the back opening for the discharge of the acid hot gases that will be conveyed into the condensing and absorbing apparatus through suitable pipes.

It will be seen that the greater is the distance between the inlet of the reacting material and the outlet of the bisulphate the longer will be the time during which said materials react on one another under the action of a high temperature. Therefore, the reaction being improved, the conveyor screw may be driven at a higher speed in the unit of time and the efficiency of the apparatus will be correspondingly increased.

Experience has shown that in order to avoid all risk of breakage owing to partial cooling, the container must be placed in a space of about constant and uniform temperature.

The annexed drawings show by way of example a diagrammatic constructional form of the apparatus according to this invention.

Fig. 1 is a longitudinal section thereof;

Fig. 2 is a view of the apparatus regulating the admission of acid.

The cast iron elliptical container 1 is provided with a cover 4 of siliceous material, a tube 2 discharging the bisulphate and a tube 3 through which the container may be cleaned during an interruption of work. At the front side of the refractory cover 4 is secured a cast iron tower carrying a cast iron filling hopper 6, through which a predetermined quantity of salt is fed into the container 1 by means of a conveyor screw 5 driven by a worm wheel 7 in the inlet tube 8. At the same time a predetermined quantity of sulphuric acid (60 or 66 Bé.) is introduced into the container 1 through a pipe 10 by means of a feeder comprising a couple of scoops 14 suspended at the ends of a rocker to which is centrally secured an arm 11 connected by means of a rod to a crank pin 9 fixed to the worm wheel keyed on the conveyor shaft.

Each scoop is provided with a long delivery pipe ending in a spout which rests on the wall of a container 12, the acid in which is kept at a constant level by the overflow

pipe 13. By the rotation of the worm wheel the scoops 14 alternately dip into the sulphuric acid in the container 12 and are then raised and pour their contents into funnels 5 provided at the ends of pipes branched from tube 10.

At the rear side of the refractory cover a tower 15 of refractory material is arranged, wherein the gradually evolved gases are collected and wherefrom the quartz tubes 16 are branched leading the said gases into the usual condensing and absorbing apparatus.

From said tube 2 the sodium bisulphate formed during the dissociation issues continually. The size of the container, as well as the distance between the salt admission point and the discharge of the sulphate are such that the reacting masses in the container under the action of the heat remain a longer time than would be necessary for the formation of the gas (HCl or HNO₃), in order to impart to the issuing bisulphate the necessary pureness, hardness and pulverizing property.

25 The above described mechanical apparatus is applied in a suitable furnace, wherein the container is completely surrounded by hot air and hot gases, while the hopper containing the salt, the container 12 and the acid regulating apparatus 14 are outside the oven and the tower 15 for the evolved acid gases as well as the end of the sulphate discharging tube project out of the oven.

30 The sulphuric acid in excess, issuing from the overflow pipe 13 of the container 12 of the acid regulating apparatus is returned

40 into the collector by means of a pump. The bisulphate issuing continually from the tube is conveyed into cast iron moulds or small wagons.

What I claim is:

Apparatus for the continuous production of hydrochloric or nitric acid and sodium bisulphate, comprising an oven, a single elongated container mounted wholly within the latter, a cover of fire-proof material tightly closing the container and also wholly within the oven whereby burnt gases circulate all about the container and ensure within the latter a constant and uniform temperature, 45 a single conduit at one end of the cover through which the re-acting agents are fed into the container, a delivery tower for the gaseous discharge at the other end, said conduit and tower projecting outwardly through the oven roof, means at the outer end of said conduit for feeding the re-acting agents in regulated quantities, and a tube for the continuous discharge of the bisulphate, having its inlet end dipping into the liquid mass at 50 a point near the bottom of the container substantially below the point of gaseous discharge, and remote from the inlet for the re-acting agents whereby a complete reaction of said agents is insured, the other end of said tube passing through the container at the normal liquid product level therein to maintain said level constant by continuous discharge.

55 In testimony that I claim the foregoing as my invention, I have signed my name.

GIUSEPPE GUADAGNI.
